UNITED STATES PATENT OFFICE.

FRANK L. GORMLEY, OF BROOKLINE, MASSACHUSETTS, ASSIGNOR TO A. O. NORTON, INC., OF BOSTON, MASSACHUSETTS, A CORPORATION OF MAINE.

LIFTING-JACK.

1,378,226.

Specification of Letters Patent. Patented May 17, 1921.

Application filed September 3, 1920. Serial No. 408,012.

To all whom it may concern:

Be it known that I, FRANK L. GORMLEY, a citizen of the United States of America, and a resident of Brookline, in the county 5 of Norfolk and Commonwealth of Massachusetts, have invented certain new and useful Improvements in Lifting-Jacks, of which the following is a specification.

This invention relates to lifting jacks and 10 particularly to devices of this character designed for heavy work, the object of the present invention being the provision of means whereby the load may be held in raised position by means of suitable holding mechanism, which holding mechanism may be released to permit the load to be lowered under its own weight and may be actuated to regulate the lowering of the movable member and prevent it from moving 15 at an excessive speed.

Another object of the invention is the provision of means whereby all of the actuating and holding mechanisms and speed regulating devices may be removed readily 20 from the jack standard.

The invention consists primarily in providing the jack standard with a removable side plate on which are mounted the mechanisms for actuating and holding the main 25 lifting screw and also the devices for controlling the speed of lowering of the movable member.

The invention further consists in certain 30 novel features of construction and arrangement of parts which will be fully understood by reference to the description of the drawings and to the claims to be hereinafter given.

For the purpose of illustrating the invention, one preferred form thereof is illustrated in the drawings, this form having been found to give satisfactory and reliable 35 results although it is to be understood that the various instrumentalities of which the invention consists can be variously arranged and organized and the invention is not limited to the precise arrangement and organization of these instrumentalities as herein shown and described, except as required by 40 the scope of the appended claims.

Of the drawings:

Figure 1 represents a horizontal section of a lifting jack embodying the principles

of the present invention, the cutting plane being on line 1, 1, on Fig. 2.

Fig. 2 represents a vertical section of the same on line 2, 2, on Fig. 1.

Fig. 3 represents an inside elevation of the removable side plate with the actuating parts mounted thereon, the main actuating 60 shaft being shown in section.

Fig. 4 represents a horizontal section of the same on line 4, 4, on Fig. 3.

Fig. 5 represents a vertical section of the same on line 5, 5, on Fig. 4.

Fig. 6 represents a vertical section of the same on line 6, 6, on Fig. 4, and

Fig. 7 represents an elevation of the brake-arm actuating lever.

Similar characters indicate like parts 70 throughout the several figures of the drawings.

In the drawings, 10 represents a suitable base supporting a stationary standard 11 over the outer periphery of which is fitted 75 a movable sleeve 12, to the upper end of which is threaded a cap 13.

In the upper end of the standard 11 is mounted a nut 14 to which is threaded a lifting screw 15 having splined to its upper 80 reduced end a bevel gear 16 with which meshes a bevel gear 17 formed upon or secured to a revoluble shaft or spindle 18, the outer end of which is provided with a suitable operating mechanism 19 of any well 85 known construction.

Between the upper face of the bevel gear 16 and the inner face of the cap 13 are two annular plates 20, 21, between which are interposed a plurality of anti-friction members 22.

The movable member 12 is provided on one side with a flanged projection 24 having a removable plate 25 secured thereto by bolts 25*.

The plate 25 is provided with a gland 26 having a bearing 26* for the spindle or shaft 18 and secured to the hub of the gear 17 is a ratchet wheel 27.

The gland 26 extends beyond the inner 100 face of the plate 25 forming a boss or support 28 and on this boss 28 is loosely mounted the gear wheel 29 having secured to one face thereof a plurality of pawls 30 coacting with said ratchet wheel 27.

The gear 29 is provided with a plurality

55

of projections 31 to the outer ends of which is secured a ring 32 between which and said gear the pawls 30 are positioned.

From the back of the free end of each 5 pawl 30 extends a lug 33 on which is disposed a helical spring 34 the outer end of which bears against one of the projections 31 and retains said pawls 30 in engagement with said ratchet wheel 27 under normal 10 conditions.

Beneath the gear wheel 29 is a revolute shaft 35 having secured thereto, a pinion 36 meshing with said gear 29 and driven thereby when the movable member 12 of the 15 jack is being lowered.

The shaft 35 has also secured thereto a worm wheel 37 which meshes with a worm 38 revolute in bearings 39 in the bracket 40 secured to the inner face of the removable plate 25 by screws 40^x.

To the reduced end 41 of the worm 38 is secured a flanged bushing 41^x forming a support for the freely revolute brake disk 42 with the periphery of which coacts two 25 brake members 43 pivoted at 44 to the bracket 40.

The lower end of each brake member 43 is provided with a recess 45 in which is positioned one end of a helical spring 46 the 30 opposite ends of said springs being disposed in the recesses 47 and 48 in the removable plate 25 and bracket 40.

Between the lower adjacent ends of the 35 brake members 43 is positioned a flat sided projection 49 formed upon the actuating lever 50.

A portion of the flat sided projection 49 is cylindrical and positioned in a cylindrical hole in the flange of the removable 40 plate 25.

The springs 46 normally retain the brake 45 members in contact with the periphery of the disk 42 and prevent its rotation until the actuating lever 50 is moved to cause said flat sided projection 49 to separate said 50 brake members 43 and remove them from contact with the disk 42.

The worm 38 is provided at its opposite end with a reduced end 51 to which is secured a gear 52.

The gear 52 meshes with the pinion 53 on one end of a shaft 54 parallel with the worm 38 while the opposite end of said shaft 54 has secured thereto a gear 55 meshing with a pinion 56 on the hub of which the brake wheel 42 is secured.

The shaft 54 revolves in a long bearing 57 formed in the bracket 40.

The flange of the bushing 41^x prevents 60 the displacement of the pinion 56 and the brake wheel 42 secured thereto and revolute therewith.

A stop pin 59 projects from the end of the removable plate or cover 25 and serves 65 to limit the movement of the lever 50 in the

direction of the arrow *a* on Fig. 7 of the drawings.

This plate 25 is also provided with a flange 60 extending outwardly therefrom which flange not only serves to limit the movement of the lever 50 in a direction opposite to that indicated by the arrow *a*, but also serves to prevent the lever from being accidentally hit and moved from its normal position as indicated in said Fig. 7. 75

When the lever 50 is in the position shown in Fig. 7, the cam member 49 is in the position shown in Fig. 6 and the brake members 43 are in contact with the brake wheel 42 and the friction between these 80 members 43 and said wheel 42 is sufficient to hold the load in raised position.

By providing a train of gears between the gear 52 secured to one end 51 of the worm 38 and the pinion 56 loosely mounted upon the bushing 41^x secured to the opposite end of the worm 38, the brake wheel 42 is revolved at a speed greatly exceeding the speed of rotation of said worm 38 and consequently a light contact of a brake member 43 on the periphery of said wheel 42 will control the speed of lowering of the movable member 12 of the jack. 90

By manipulating the lever 50 any degree of frictional contact between said brake members 43 and brake wheel 42 may be secured and consequently any speed of lowering may be attained. 95

If the operator releases the lever 50 when moved from stop pin 59 in the lowering of 100 the jack, the springs 46 will immediately return the lever 50 to the position indicated in Fig. 7 and the brake arms to their normal position in contact with the brake wheel 42 thus interrupting the lowering of the 105 jack.

The means employed of securing a high speed to the brake wheel 42 loosely mounted upon one end of the worm 38 from a driving member secured to and revolute with 110 the other end of said worm, is simple and compact occupying but little space which obviously is of great advantage particularly in the manufacture of the smaller sizes of jacks. 115

Moreover, the parts are more readily assembled and the operating parts are provided with better bearing surfaces thereby insuring longer life to the jack and less liability of its being placed temporarily out of commission. 120

All of the actuating parts are mounted upon a single side plate which may be removed quickly to give access to the interior of the jack or to repair or replace any of the 125 moving parts on said plate.

Old style jacks having no devices for automatically controlling or retarding the lowering of the movable member 12 under the weight of the load may be changed read- 130

ily into self-run-down jacks by simply removing the old side plate and substituting therefor the side plate herein shown and described with its actuating parts secured thereto.

The worm shaft 61 has a cup-shaped member 62 mounted thereon abutting the housing 63 for the gear 52 and a washer 64 abutting the end of the worm 38 and between the cup-shaped member 62 and washer 64, are a plurality of anti-friction members 65 adapted to take care of the end thrust of the worm during the lowering of the jack.

15 The pitch of the worm 38 is such that during the rotation of the worm gear 37 rotary movement will be imparted to the shaft 61 and the gear 52.

When it is desired to raise the movable member 12, the operating mechanism 19 is manipulated to turn the spindle 18 and gear 17 formed thereon in the direction of the arrow *b* on Fig. 3 of the drawings.

25 When this is done, the ratchet 27 will freely pass the pawls 30 without actuating the spur gear 29.

While lifting the load the operating mechanism will act directly upon the movable member 12 without affecting the speed retarding and braking devices.

30 When the weight has been lifted sufficiently, it will be retained in its elevated position by means of the friction members 43 coacting with the brake disk 42 and preventing the rotation of the worm 38.

When it is desired to lower the load supported by the movable member 12, the friction members 43 are removed from contact with the disk or wheel 42 by pressing upon 40 the arm or lever 50 and with the pawls 30 in engagement with the teeth of the ratchet 27, the gear 29, pinion 36, worm wheel 37 and worm 38 will be driven by the rotation of the gear 17 and its spindle 18.

45 The pitch of the worm thread is such as to permit the jack to start automatically to descend under its own load when its brake is released.

Should an excessive load be upon the cap 50 13 so that member 12 moves downwardly too rapidly, its movement will be arrested by the manipulation of the lever 50.

If it is desired to entirely stop the lowering of the load, pressure is removed from the 55 actuating lever 50 and the brake members 43 will be forced into contact with the disk 42.

The multiplication of the braking power through the high ratio gearing and through the worm and worm wheel will serve to make 60 possible the quick and easy stoppage by a light pressure of the brake, of the descending jack at any point.

It is believed that the operation and many 65 advantages of the invention will be readily understood without further description.

Having thus described my invention, I claim—

1. In a lifting jack, a revoluble operating shaft; a revoluble gear in axial alinement therewith; means on said shaft for rotating 70 said gear in one direction only and that during the lowering operation; a worm adapted to be rotated by said gear; a gear secured to one end of said worm; a pinion meshing therewith; a shaft parallel to said worm to one end of which said pinion is secured; a gear secured to the opposite end of said parallel shaft; a pinion freely revoluble about the axis of said worm and meshing with the gear on said parallel shaft; a brake 80 wheel revoluble with the last-mentioned pinion; and means coacting with said brake wheel for normally preventing the rotation thereof.

2. In a lifting jack, a revoluble operating 85 shaft; a worm; means interposed between said shaft and worm for rotating the latter only during the lowering operation; a gear secured to one end of said worm and revoluble therewith; a pinion revoluble about the 90 axis of said worm and independently thereof; mechanism for imparting rotary movement to said pinion from said gear; and braking mechanism revoluble with said pinion.

3. In a lifting jack, a revoluble operating 95 shaft; a worm; means interposed between said shaft and worm for rotating the latter only during the lowering operation; a gear secured to one end of said worm and revoluble therewith; a pinion revoluble about the 100 axis of said worm and independently thereof; mechanism for imparting rotary movement to said pinion from said gear; a brake wheel revoluble with said pinion; and means coacting 105 with said brake wheel for normally preventing the rotation thereof.

4. In a lifting jack, a revoluble operating 110 shaft; a worm; means interposed between said shaft and worm for rotating the latter only during the lowering operation; a gear secured to one end of said worm and revoluble therewith; a pinion revoluble about the 115 axis of said worm and independently thereof; mechanism for imparting rotary movement to said pinion from said gear; and a speed retarding device adapted to be operated by said pinion.

5. In a lifting jack, a revoluble operating 120 shaft; a worm; means interposed between said shaft and worm for rotating the latter only during the lowering operation; a brake wheel mounted upon one end of said worm and adapted to rotate independently thereof; means driven from the opposite end of 125 said worm for rotating said brake wheel at a speed greatly exceeding the speed of said worm; and means coacting with said wheel for normally preventing the rotation thereof.

6. In a lifting jack, a revoluble operating shaft; a revoluble gear adapted to be rotated thereby in one direction only and that during the lowering operation; a worm; mechanism actuated by said gear for rotating said worm; a speed controlling member alined with said worm and rotatable independently thereof; and a train of gears between said worm and speed controlling member for rotating the latter at a speed greatly exceeding that of the former.
7. In a lifting jack, a revoluble operating shaft; a revoluble gear adapted to be rotated thereby in one direction only and that during the lowering operation; a worm having reduced threaded ends; mechanism actuated by said gear for rotating said worm; a flanged sleeve on one threaded end; a pinion freely revoluble thereon; a speed controlling member secured to and revoluble with said pinion; and a train of gearing for rotating said pinion, the initial driving gear of which is secured to the other threaded end of said worm.
8. In a lifting jack, a revoluble side plate; a flanged gland therein; an operating shaft revoluble in said gland; a gear revoluble about the inner end of said gland; means mounted on and revoluble with said shaft for rotating said gear in one direction only and that during the lowering operation; a revoluble worm mounted on said plate; means actuated by said gear for rotating said worm; a speed retarding device mounted on one end of the worm and rotatable independently thereof; a driving member secured to the other end of said worm and revoluble therewith; and means interposed between said retarding device and said driving member and actuated by the latter for imparting rotary movement to said retarding device at a speed greatly in excess of that of said driving member.
9. In a lifting jack, a removable side plate

provided with a lateral bearing; an operating shaft revoluble in said bearing; a freely revoluble gear alined with said shaft; means on said shaft for rotating said gear in one direction only and that during the lowering operation; a bracket secured to the inner face of said plate; a shaft having bearings in said plate and bracket; a pinion revoluble with said shaft and driven by said gear; a worm gear also revoluble with said pinion shaft; a worm revolubly mounted in said bracket and adapted to be driven by said worm gear; a speed retarding device mounted on said worm; and means driven by said worm for rotating said retarding device at a speed greatly in excess of that of said worm.

10. In a lifting jack, a removable side plate provided with a lateral bearing; an operating shaft revoluble in said bearing; a freely revoluble gear alined with said shaft; means on said shaft for rotating said gear in one direction only and that during the lowering operation; a bracket secured to the inner face of said plate; a shaft having bearings in said plate and bracket; a pinion revoluble with said shaft and driven by said gear; a worm gear also revoluble with said pinion shaft; a worm revolubly mounted in said bracket and adapted to be driven by said worm gear; a speed retarding device mounted on said worm; a driving gear rotated by said worm; and a train of gears actuated by said driving gear for rotating said retarding device at a speed greatly in excess of that of said worm.

Signed by me at 746-7 Old South Bldg., Boston, Mass., this 1st day of September, 1920.
